G. STROM

POURED WALL FORM

Filed July 23, 1923

UNITED STATES PATENT OFFICE.

GUSTAV STROM, OF PONTIAC, MICHIGAN, ASSIGNOR OF FORTY ONE-HUNDREDTHS TO
PETER D. JOHNSTON, OF PONTIAC, MICHIGAN.

POURED-WALL FORM.

Application filed July 23, 1923. Serial No. 653,230.

The invention relates to forms for poured building walls and has for one of its objects the provision of a simple construction of form which provides for reinforcing bridge members between the spaced outer and inner wall sections of the poured wall and which may be readily assembled and after the pouring of the wall, dis-assembled and withdrawn so that it may be used again. Another object is the provision of a form comprising spaced side sections and end sections movable transversely of and between the side sections, the sections having cooperating bearing surfaces which permit the side sections to move toward each other when the end sections have been moved transversely inward relative to the side sections. Further objects of the invention reside in the novel features of construction and combinations and arrangements of parts as more fully hereinafter set forth.

In the drawings:

Figure 1 is a perspective view of a portion of a building in the course of construction and showing a form embodying my invention;

Figure 2 is a plan view of the form;

Figure 3 is a perspective view thereof;

Figure 4 is an enlarged plan view partly in section, showing the method of securing the form sections in place;

Figure 5 is a perspective view of the securing clip.

As shown in Figure 1 the building wall has the spaced outer and inner wall sections 1 and 2 respectively between which extend the vertical series of integral zig-zag diagonal or inclined bridge members 3 which are integral with the outer and inner wall sections. These bridge members are preferably hexagonal in cross section.

For the purpose of providing forms for this building wall which may be readily assembled and which, after the wall has been poured, may be readily disassembled and withdrawn, I have provided the series of outer and inner side sections 4 and 5 and the series of end sections 6 and 7, the adjacent end sections cooperating to form the bridge members 3. As shown particularly in Figures 2 and 3, the side sections 4 and 5 are alike and are formed of sheet metal plates preferably having inturned ends 8. These plates are reinforced by the vertically extending angle bars 9 and by the horizon-

tally extending angle bars 10 near the upper and lower ends thereof. The vertically extending angle bars are spaced inwardly from the side edges of the plates a sufficient distance to permit of the transverse inward movement of the end sections 6 and 7 a sufficient distance to become disengaged from the bridge members. The end sections 6 and 7 are provided on the outer faces with the diagonal or inclined recess 11, each having three sides to form one-half of each bridge member. The adjacent end sections are provided with registering recesses, which together form a complete bridge member. To hold the side and end sections firmly in place while the wall is being poured, I have provided the hooks 12 which are pivotally connected to the outer vertically extending bars 9 of one side section and are adapted to engage pins 13 extending from the outer vertically extending bar 9 upon the other side section.

For the purpose of permitting of the ready disassembly and withdrawal of the side sections 4 and 5 and end sections 6 and 7, the latter are preferably tapered outwardly so that upon their transverse inward movement relative to the side sections, the side sections can be moved inwardly toward each other, after which all of the sections may be pulled upwardly from the wall. However, before moving the end sections inwardly, the hooks 12 are disengaged.

To permit of building the forms up preparatory to pouring the building wall, the upper horizontally extending angle bars 10 are provided with vertically extending pins 14 and the lower horizontally extending angle bars 10 are provided with apertures which register with the vertically extending pins when the sections have been correctly positioned in alignment with each other.

15 and 16 are side members of the outer form on opposite sides of and spaced from the side sections 4 and 5 of the inner form, the side members of the outer form being preferably formed of sheet metal plates reinforced by vertically extending angle bars 17 and horizontally extending angle bars 18. To secure the side members of the outer form together and at the same time to position them in correct relation to the side sections of the inner form, there is the bar 19 extending transversely of and between the 114

adjacent end sections 6 and 7 of the inner form as well as between the adjacent flanges 20 of the outer vertically extending angle bars 17. The bar 19 has the struck-out 5 tongues 21 intermediate its ends for engaging the sides of the end section 7, the adjacent end section 6 being positioned by means of the hook 22 pivoted upon the end section 7 and detachably engaging the pin 10 23 upon the end section 6. 24 is a U-shaped clip having the transversely extending projection 25 upon one of its legs for engaging in registering openings in the adjacent flanges 20 of the angle bar 17 and in the bar 15 19 to position the side members of the outer form relative to the side sections of the inner form and also to align the sides of the outer form with each other. The other leg of the clip 24 is longitudinally slotted at 26 to form bifurcations engageable on opposite sides of 20 the adjacent flanges 20 of the angle bars 17 to hold the adjacent side members of the outer form together.

With this arrangement, it will be readily 25 seen that I have provided a simple construction of form for building walls in which the side sections and side members are detachably held in correct position relative to each other and may be readily assembled and dis- 30 assembled. It will also be seen that with my arrangement the end sections upon the transverse movement relative to the side sections of the inner form will permit of movement of the side sections toward each other 35 and also that these end sections serve to position the side sections of the inner form relative to the side sections of the outer form. A further feature resides in the arrangement of transverse bar and clips at the ends 40 of this bar for holding the side sections and members of the form in their correct relative positions, the arrangement of bar and clips being such that they may be formed of stampings at a comparatively low cost.

45 What I claim as my invention is:

1. In a poured wall form, the combination with spaced side sections, of end sections movable between said side sections, each end section being provided with inclined transverse recesses in one of its faces.

50 2. In a form for a poured wall having spaced inner and outer wall sections and integral diagonal bridge members therebetween, the combination with spaced side sections, of end sections movable between said side sections, said end sections having transverse diagonally extending recesses in their outer faces and adjacent end sections having their recesses registering to form the diagonal bridge members for the wall.

55 3. In a poured wall form, the combination with spaced side sections, of end sections slidably movable inward of and between said side sections, said sections having braces normally maintaining the spaced

relation of the side members and arranged to permit of the movement of said side sections toward each other upon the transverse movement of said end sections inwardly relative to said side sections.

4. In a poured wall form, the combination with spaced side sections, of end sections movable inward of and between said side sections, said end sections being provided with diagonal recesses in their outer faces, and tapering outwardly to permit of the movement of said side sections to each other when said end sections have been moved transversely inward.

5. In a poured wall form, the combination with spaced side sections comprising plates having inturned edges, of outwardly tapered end sections movable between said side sections, each end section having inclined recesses in its outer face.

6. In a poured wall form, the combination with spaced side sections, of end sections provided with inclined recesses extending transversely thereof.

7. In a form for a poured wall having spaced inner and outer wall sections and diagonal integral bridge members therebetween, the combination with spaced side sections, of end sections having transverse diagonally extending recesses in their outer faces and adjacent end sections having their recesses registering to form the diagonal bridge members for the said inner and outer wall sections.

8. In a poured wall form, the combination with spaced side sections, of end sections projecting beyond said side sections and provided with recesses extending transversely thereof, adjacent end sections of successive forms registering and hooks engaging said end sections for maintaining alignment of said forms.

9. Means for pouring a hollow wall comprising an outer form and an inner form, a plurality of longitudinally aligned side members included in said outer form and a plurality of longitudinally aligned side sections included in said inner form, a one-piece bar extending transversely of the meeting portions of adjacent longitudinally pairs of outer and inner forms, and means cooperating with said bar for holding the successive longitudinally adjacent pairs of outer and inner forms in aligned relation.

10. A form for a poured wall having spaced inner and outer wall sections and diagonal integral bridge members therebetween, said form having spaced side sections, and means for forming said diagonal integral bridge members between the wall sections.

11. In a form, the combination with inner and outer molds, the latter including a plurality of side members having adjacent flanges at their edges, of a bar extending

transversely of said side members and between said flanges, means on said bar for positioning said inner mold and a U-shaped clip having one leg thereof formed with a bifurcated portion adapted to receive said flanges and the other leg thereof adapted to be extended through aligned openings in said flanges and bar.

12. In a form, the combination with inner and outer molds, the latter including a plurality of side members having adjacent

flanges at their edges, of a bar extending transversely of said side members and between said flanges, said bar having tongues struck out therefrom for locating said inner mold, and a clip formed at one end with a bifurcated portion for embracing said flanges, and at the other end with another portion adapted to be extended through said flanges and bar.

In testimony whereof I affix my signature.
GUSTAV STROM.
